RIBBON ACTUATING MECHANISM

Walter Dieck, Erfurt-Hochheim, Germany

Application January 7, 1941, Serial No. 373,510
In Germany December 28, 1939

5 Claims. (Cl. 197—159)

The invention relates to typewriters and similar recording machines and particularly to mechanism for actuating the ink ribbon vibrator thereof.

More particularly, the invention relates to improvements in ribbon vibrating mechanism in which the individual key levers or type levers of the type action cooperate with a universal bar which through suitable connections lifts the ribbon vibrator to shift the ribbon into printing position beneath the type bars when the machine is operated to cause one of the type-bars to move to printing position against the platen.

It is known to provide mechanism for lifting the ink ribbon vibrator uniformly during the duration of and coincidentally with the entire stroke of the type bars so that both the type head and ink ribbon assume the final printing position substantially simultaneously. For accurate and neat work, it is desirable to bring the ribbon vibrator into printing position in advance of the completion of the printing stroke of the type bars so that the ribbon is at rest in the printing position at the time the type head impinges on the same to effect printing. However, the provision for movement of the ribbon vibrator to final position in advance of the type bars results in the vibrator engaging its limiting stop before the end of the stroke of the type bar and universal rail actuated thereby so that unless some special construction is provided the free motion of the type bars and universal bar will be interfered with. While this difficulty might be met by the introduction of spring connections permitting further motion of the universal bar after stopping of the ribbon vibrator, the use of spring connections is not practical if the ribbon vibrator is to be actuated with exactness and further the additional force required for overcoming the tension of the spring is objectionable.

It is the primary object of the invention to provide improved means for transmitting motion from the universal bar to the actuating connections for the ribbon vibrator which will effect accelerated lifting of the ribbon vibrator to printing position in advance of completion of the stroke of the type bars and provide for unhindered completion of the stroke of the type bars and motion of the universal bar after the ribbon vibrator has reached and while it remains at rest in the upper or printing position.

According to a preferred embodiment of the invention, the drawbacks discussed above and the objects of the invention are achieved by the

provision of an adjustable cam connection between the universal bar and the lever system actuating the ribbon vibrator, the cam connection being shaped to provide for rapid movement of the ribbon vibrator to printing position upon initial movement of the universal bar by the type action and permitting free over-running movement of the universal bar and type bars with respect to the ribbon vibrator during the latter part of the printing stroke after the ribbon vibrator reaches and remains at rest in the upper or printing position.

The objects and advantages of the invention will be better understood by reference to the accompanying drawing, in which a preferred embodiment thereof is shown by way of example, and in which:

Fig. 1 is a fragmentary sectional view through a typewriter embodying the invention, showing the parts in a position of rest, and

Fig. 2 is a similar view showing the disposition of the parts as the type bar approaches final printing position.

Referring more particularly to the drawing, wherein only so much of the typewriter mechanism has been shown as is necessary to an understanding of the invention, the type action comprises a key lever 1, an intermediate rocking lever 2 and a type lever 3. The key lever is connected by a link 4 to one end of the intermediate lever 2 and a pull rod 5 connects the other end of the lever 2 to the heel of the type lever 3 which is pivotally mounted on the type segment 6.

The segment 6 which mounts the type levers is formed to provide a guide and mounting for the ribbon vibrator 7 which carries the ribbon 8. These parts are usual on typewriters and their construction and mode of operation are well understood, depression of the key lever 1, through link 4, lever 2 and rod 5, throws the type lever from the at-rest position of Fig. 1 through the position shown in Fig. 2 to cause the type head to strike the platen 9, the ribbon vibrator being meanwhile raised to printing position so that the ribbon carried thereby is shifted into a position between the type head and the platen.

For the sake of simplicity, the color zone selecting means, usually associated with the ribbon mechanism has been omitted.

The lever system for actuating the ribbon vibrator 7 comprises a lever 10, pivotally connected at one end to the vibrator 7, as indicated at 7a. The lever 10 is mounted intermediate its ends on a stationary bearing pivot 11 and

has its other end pivotally connected with the end of one arm of a bell-crank lever 12 which latter is mounted on stationary pivot bearing 13. The connection between the lever 10 and bell crank 12 may be formed by engaging the hooked end of the arm through an aperture in the end of the lever. A spring 12a connected between the arm of the bell crank and a stationary part of the frame urges the arm to the retracted position shown in Fig. 1.

A universal bar 14a is operated by a part of each type action. The bar extends transversely of the machine beneath the key levers in position to be engaged and depressed by the same upon the depression of any one of the keys.

The universal bar 14a has rearwardly extending side arms 14 at each end thereof by which it is journalled on horizontal pivot bolts 15 mounted on side frame members, not shown. The arms 14 each carry an upstanding lever arm 14b which branches from the same adjacent the pivot 15. Return springs 17 connected between the upper ends of arms 14b and a stationary part of the frame yieldingly return the universal bar to the position shown in Fig. 1. One of the lever arms 14b carries a projection in the form of a roller 16 journalled on a horizontal pivot pin 16a disposed substantially perpendicularly above the pivot bolt 15.

A lever arm 18, pivoted at one end on the rod 19 mounting the key levers 1, extends forwardly thereof and at its forward end is provided with a substantially vertically extending terminal portion upon which is mounted a cam element in the form of a forwardly extending curved finger member 20. The finger member 20 is carried by a plate 20a which is secured on the end of arm 18 by screws 21, the plate being slotted at 21a so that the position of the same may be adjusted. The cam finger 20 engages under and extends up in front of the roller 16 carried by the lever 14b of universal bar 14a. The slots 21a in the plate 20a extend vertically so as to permit vertical adjustment of the plate and the upper slot is made considerably wider than the diameter of the shank of the screw 21 engaged therethrough so that the inclined position as well as the vertical position of the curved cam finger 20 may be adjusted in relation to the roller 16.

A horizontal pin 18a carried by the lever arm 18, forwardly of the pivot rod 19, engages the lower arm 12b of the bell crank lever 12 when the lever 18 is depressed, thus rocking the bell crank and through the lever 10 raising the ribbon vibrator. The return spring 12a acting on bell crank 12 yieldingly holds the lever 18 in raised position with the cam finger 20 in engagement with roller 16.

The roller engaging surface of the curved cam finger 20 is formed with a contour to effect the desired movement of the ribbon vibrator in relation to the stroke of the type lever. With the parts at least, as shown in Fig. 1, the roller 16 contacts a part 22 of the surface of the finger which extends substantially coincident with the path of the roller upon depression of the universal bar. The surface part 22 merges into the cam surface 23 disposed in the path of the roller 16 at a sharp angle to said path so that the lever is rapidly depressed when the roller 16 moves from the position of Fig. 1, to the position of Fig. 2. The cam surface 23 merges into a final end surface 24, which, in the depressed position of Fig. 2, extends substantially coincident with the path of travel of the roller 16 upon continued

movement thereof, thus allowing completion of the stroke of the key lever and over travel of the universal bar after the ribbon vibrator has been shifted to its uppermost position.

5 By adjustment of the vertical position of the finger 20 and the angularity thereof with respect to the path of the roller 16, the extent and speed of movement of the ribbon vibrator with respect to the motion of the type action can be varied as desired.

10 While a preferred embodiment of the invention has been shown and described by way of illustration, it will be understood that various modifications in the details of construction and operation of the parts may be resorted to without departing from the spirit of the invention within the scope of the appended claims.

I claim:

1. In a typewriter, a platen, a type action including a type bar movable to and from printing engagement with the platen, a ribbon vibrator movable to and from the printing point on the platen, a universal bar operatively engaged by a part of the type action, a projection carried by said universal bar, an actuating linkage for said ribbon vibrator including a lever, a finger carried by said lever having a cam surface portion disposed in the path of said projection and so shaped that, upon actuation of said universal bar by said type action, said projection moves over a portion of said cam surface and actuates said lever to move said ribbon vibrator to the printing point before the type bar reaches the platen and then moves over a succeeding portion of said cam surface to maintain said ribbon vibrator at the printing point during final movement of the type bar into printing engagement with the platen.

2. In a typewriter according to claim 1, means for adjusting the position of said finger with respect to the projection carried by the universal bar.

3. In a typewriter, a platen, a type action including a type bar movable to and from printing engagement with the platen, a ribbon vibrator movable to and from the printing point on the platen, a universal bar pivoted on a horizontal axis and operatively engaged by a part of the type action, a roller carried by said universal bar spaced from the pivoted axis thereof, an actuating linkage for said ribbon vibrator including a lever, a projecting member carried by said lever having a cam surface disposed in the path of movement of said roller upon operation of said universal bar, said cam surface being so shaped that upon actuation of said type action and universal bar movement of said roller over a portion of said cam surface actuates said lever to move said ribbon vibrator to the printing point before the type bar reaches the platen and movement of said roller over a succeeding portion of said cam surface maintains said ribbon vibrator at the printing point during final movement of the type bar into printing engagement with the platen.

4. In a typewriter, a platen, a type action including a type bar movable to and from printing engagement with the platen and a key lever operatively connected with said type bar, a ribbon vibrator movable to and from the printing point on the platen, a universal bar pivoted on a horizontal axis and extending transversely beneath said key lever and operated thereby upon depression of the key lever to move said type bar into printing engagement with the platen, an

upstanding lever arm carried by said universal bar, a laterally projecting roller carried by said lever arm, an operating linkage for said ribbon vibrator including a lever pivoted on a horizontal axis and extending from said axis to adjacent said lever arm, a plate mounted on said lever having a projecting finger portion presenting a cam surface disposed in the path of movement of said roller, said cam surface including an active portion and a neutral portion so shaped that upon operation of said universal bar by depression of said key lever movement of said roller over the active portion of said cam surface actuates said lever and associated linkage to move

the ribbon vibrator to the printing point before the type bar reaches said point and movement of said roller onto the neutral portion of the cam surface upon continued motion of the universal bar maintains the ribbon vibrator stationary at the printing point during final movement of the type bar into printing engagement with the platen.

5 5. In a typewriter according to claim 4, means 10 for adjusting the position of said plate on said lever to vary the relation of said finger with said roller for regulating the amount and character of movement of said ribbon vibrator.

WALTER DIECK.
